UNIVERSALLY MOUNTABLE CLOTHESLINE
FASTENER

Robert T. Duarte, Nashua, N.H.

(Belair Trailer Park, R.F.D. 2, Reeds Ferry, N.H. 03078)
Filed Dec. 18, 1964, Ser. No. 419,441
1 Claim. (Cl. 24—137)

This invention relates to an improved, universally mountable clothesline fastener.

More specifically, this invention relates to a clothesline fastener that may be placed on a line to hold objects and may be placed on the line in an infinite number of positions.

In the prior art, there have been numerous variations of clothesline fasteners, but the users of these fasteners have always experienced a basic problem that arises when the line fasteners are placed in a bag or container for storage. Each time another fastener is needed, the person hanging the clothes or objects must reach blindly into the bag or container to select another fastener. Because the pins or fasteners are generally oblong in shape, the user has difficulty in determining whether the pin or fastener is right side up until the pin or fastener has been removed from the bag or container. If the pin is upside down, the user must fumble with the pin to change its position. This is complicated by the fact that the clothespin user's other hand is usually occupied by the manipulation of the garments or objects that are to be hung. Windy and blowing weather add further difficulties to this manipulation of the fasteners.

The clothesline fastener to be described hereafter eliminates the above noted problems in that the fastener is universally mountable. The user need not ever determine which side is up.

Therefore, it is an object of this invention to provide a universally mountable clothesline fastener.

Another object of this invention is to provide a clothesline fastener that has a multiple of clothes gripping surfaces.

Still another object of this invention is the creation of a clothesline fastener that may be readily manufactured at very low cost.

Another object of this invention is the provision of a clothesline fastener that may be easily stored for subsequent use in a variety of manners.

Other objects, features and advantages will become apparent after consideration of the following detailed specification together with the appended drawings, in which:

FIG. 1 is a three dimensional illustration of a preferred embodiment of the invention in actual usage;

FIG. 2 is a cross section of a clothesline fastener taken along lines 2—2 of FIG. 1; and

FIG. 3 illustrates a typically sectioned universal fastener with one side pressed together.

Reference is now made to FIG. 1 in which there is illustrated a typical arrangement utilizing the invention to be described hereafter.

There is shown secured to a clothesline 19 two clothesline fasteners 11 and 12, one of which is shown in partial section for purposes of illustration only. Each of the clothesline fasteners 11 and 12 is basically composed of two flattened annular disks 13 and 14 which have been joined at a central portion 18. These flattened annular disks 13 and 14 have at their outer periphery inwardly projecting lip portions 16 and 17. The function of these inwardly projecting lip portions 16 and 17 is to enhance the gripping of the clothesline 19 at two distinct points on the line 19 as can best be observed from a study of the left hand portion of FIG. 1, where the clothesline fastener 11 is shown gripping the garment 21 at two distinct gripping points 23 and 24. These two gripping

2

points which will always be present when the clothesline fastener is placed on a line, such as clothesline 19, serve an important function of insuring the multiple gripping of the garment to be held on the line 19.

5 The clothesline fasteners 11 and 12 may be formed of any suitable plastic material. They may be made into their present form by injection molding or they may be formed from solid rods of plastic or metal by conventional lathe operations which would form the lip portions 16 and 17 in a wholly conventional manner.

10 The clothesline fasteners depicted are shown to be of a plastic material, but it is to be understood that the invention contemplates the utilization of other materials such as metal in the form of stamped annular disks which could then be spot welded at the central portion to provide the necessary point of flexure for the clothesline fastener.

15 FIG. 2 illustrates a cross section of a typical clothesline fastener showing the relationship of the clothesline 20 19 to the garment 21 and the lip portions 16 and 17 which are located at the periphery of flattened disks sides 13 and 14. The central portion 18 joining these two flattened sides 13 and 14 should be of a resilient material in order that some flexure can occur at this point 25 of interconnection.

20 The flexure of the clothesline fastener is best seen in a study of FIG. 3 which shows a thumb and index finger 26 and 27, in a gripping relationship to a clothesline fastener 28. As can be seen in this figure, the pressing together on one side of the clothesline fastener 28 spread 30 apart the diametrically opposite sides of the clothesline fastener to thereby enhance the insertion of the line and garment between the gripping areas of the clothesline fastener.

35 In all three of the figures, FIGS. 1, 2 and 3, there is illustrated a centrally bored opening 22. This centrally bored opening may be utilized to assist in the mounting of the clothesline fastener on a suitable rod element not illustrated in the figures. The rod which has not been 40 illustrated may be mounted near the clothesline and as the clothesline fasteners are needed, they may be withdrawn from the rod and placed on the line. On the other hand, if the clothesline fasteners should be stored within a container, whenever one is needed, it may be readily withdrawn from the container with no concern 45 whatsoever as to whether or not the clothesline fastener is in the correct attitude for insertion on the line, because no matter what way the clothesline fastener is picked up, it is universally mountable on the clothesline in the manner illustrated in FIG. 1.

50 It is therefore evident that the new and improved clothesline fastener presents a most unique solution to the problems that have plagued the homemaker using prior art clothespins which were described at the outset.

55 It should be further understood that while the embodiment described is directed to the use of the described fastener for garments, the fastener may be used for any gripping function where a line or wire is involved.

60 While there has been hereinbefore described what is considered a preferred embodiment of the invention, it will be apparent that many and various changes and modifications may be made with respect to the embodiment illustrated, without departing from the spirit and scope of the invention. It will be understood, therefore, that all changes and modifications as fall fairly within the scope of the present invention as defined in the appended claim are to be considered as part of the present invention.

65 What is claimed is:

70 A universally mountable clothesline fastener to be mounted on a clothesline comprised of
(a) two flattened annular disks spaced apart and

joined at a central portion of said flattened annular disks to provide a clothesline fastener that may be slipped over a clothesline fitting between said flattened annular disks, and

- (b) said central portion having a resilient characteristic to thereby permit said flattened disks to be pressed together at any portion of said periphery which results in said flattened disks separating diametrically opposite the pressed together portion to thereby facilitate the gripping of said clothesline,
- (c) said flattened annular disks each having a continuous peripherally located inwardly projecting lip,
- (d) said clothesline physically cooperating with said inwardly projecting continuous lip so as to always provide two distinct gripping points on the periphery of each of said flattened disks to thereby always provide a multiple gripping action upon said clothesline and any object to be secured to said clothesline in a completely universal manner so that the clothes-

line fastener may be utilized without any regard to the manner in which it is handled for use as a fastener.
